US00D768487S

(12) **United States Design Patent** (10) **Patent No.:** **US D768,487 S**
(45) **Date of Patent:** **** Oct. 11, 2016**

(54) **LID**

(71) Applicant: **YETI Coolers, LLC**, Austin, TX (US)

(72) Inventors: **Roy Joseph Seiders**, Austin, TX (US);
Steve Nichols, Austin, TX (US);
Matthew Joseph Petrillo, Austin, TX (US)

(73) Assignee: **YETI Coolers, LLC**, Austin, TX (US)

(**) Term: **15 Years**

(21) Appl. No.: **29/544,227**

(22) Filed: **Oct. 30, 2015**

(51) **LOC (10) Cl.** **09-07**

(52) **U.S. Cl.**

USPC **D9/443**; D7/392.1; D7/396.2; D9/434;
D9/435; D9/436; D9/454

(57) **CLAIM**

The ornamental design for a lid, as shown and described.

DESCRIPTION

FIG. 1 is a top, front, right perspective view of a lid showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines represent environmental subject matter that forms no part of the claimed design.

1 Claim, 4 Drawing Sheets
